APPARATUS FOR MAKING PORTLAND CEMENT

Thorkild Avnsoe, Bellerose, N. Y., assignor to International Cement Corporation, New York, N. Y., a corporation of Maine

Original application December 26, 1931, Serial No. 583,268. Divided and this application December 29, 1932, Serial No. 649,253

6 Claims. (Cl. 222—7)

This application is a division of Serial No. 583,268, filed December 26, 1931, by Harvey Randolph Durbin and myself.

This invention relates to an improved apparatus for introducing into a kiln materials to be treated therein, which apparatus is particularly suited for cement kilns or the like where hot gases are encountered. An object of the invention resides in the provision of an improved construction whereby the mix may be introduced into an ordinary rotary kiln through openings in the wall thereof and at the desired point, and without the loss of heat at the point of introduction. In this connection, a further object is to provide such a construction in which back firing from the kiln is prevented, without the use of valves, in the introduction pipes. Another object is to provide such a construction which is readily adaptable to permit operation of the kiln when the material is introduced above said openings.

In connection with a more detailed description of the invention, reference will be had to the accompanying drawings, wherein:

Fig. 1 is a diagrammatic side view of a kiln in accordance with the present invention, showing means, partly in section, for introducing Portland cement mix into the kiln.

Fig. 2 is an enlarged transverse section of the construction shown in Fig. 1, taken through the means for introducing the mix.

Fig. 3 is a fractional side elevation showing the means carried by the kiln for introducing the mix into the latter.

Fig. 4 is an enlarged central, cross-sectional view of means for detachably securing to the kiln the tubes for introducing the mix thereinto.

Fig. 5 is a transverse section taken on the line 5—5 of Fig. 4.

Figs. 6 and 7 are views similar to Figs. 4 and 5, respectively, but showing the kiln with the tube removed and means in place for closing an opening in the kiln.

Referring now to the drawings, there is shown at 1 a rotary kiln adapted to the burning of mixtures of the material to be combined to form Portland cement. This kiln may be suitably supported for rotation and rotated in any known manner, and suitable means provided at its material inlet end 2 for feeding the cement mixture for the first burning. Hot gases may be fed to the material discharge end 3 of the kiln in any convenient manner, for example, as illustrated at 3a from a gas, oil, or coal burner. There is shown generally at 4 in Fig. 1 means for introducing the mix for the second burning in accordance with the present process. This means consists of a hopper 5 into which the mixture of lime and once burned cement 6 may be fed through any suitable screw conveyor, or the like,

for instance, as shown at 7. This hopper may be closed at the top by a roof 8 which may extend over the kiln. In order to pick up the material from the hopper and feed it into the kiln, the latter may be provided as shown with a series of tubes 10, the outer ends 11 of which are adapted to scoop up quantities of the mix as the kiln revolves, while the inner ends of these tubes 12 extend through the side wall of the kiln and enter the interior thereof.

In order to avoid the danger of back-firing and loss of heat from the kiln into the hopper, on account of the difference in temperature between the interior of the kiln and the hopper, we prefer to make these tubes 10 of such length that there is always sufficient material in each tube during the operation of the kiln in carrying out the second burning to prevent back-firing and back pressure. In this manner, before one quantity of mix has entirely passed through a given tube 10 into the interior of the kiln, the other end of the tube is picking up another portion of the mix. For this purpose, it is advantageous to have the tubes generally circular or, in other words, with their inner and outer ends 12 and 11 located about 360° apart. However, depending on how much material is generally taken in by the tube at each revolution, the tubes may be somewhat shorter or longer. While any desired number of tubes of this character may be employed, four are shown in Fig. 2, supported on the kiln through any suitable hangers 13, 13.

In order that the kiln may be used intermittently for the first and second burning operations, it may be provided with removable tubes 10 or with removable connecting sections as shown in Figs. 4-7. For instance, the kiln outer metal wall, shown at 20, has a lining 21 of refractory material which is secured to the wall 20 in any suitable manner. An opening 22 is formed both through the refractory material and the outer wall, but the outer wall may advantageously extend partly over the opening in the refractory material, for purposes hereafter indicated. Hollow castings 23 having flanges 24 are secured to the wall of the kiln and pass through and fill the hole in the refractory material. The connecting section 12 of the tube 10 has a flange 13a which may be integral with the corresponding flange on the main body of the tube 10 or detachable therefrom and held by bolts or other suitable clamping means. This tube 12 is curved to extend from a direction generally parallel to the circumference of the kiln, into the opening in the casting 23 and to communicate with the interior of the kiln. The tube 12 is provided with a rim 25 for engaging the outer sides of the wall of the kiln around the opening 22, to form a tight closure. A lug

27, which may be beveled out to receive the tube 12, is provided on the kiln for positioning the rim 25. A lug 26 is formed on the rim 25 and a surface 29 is provided to abut against the edge 5 of the wall 20. For maintaining the tube end 12 in engagement with the walls of the kiln, the lug 26 is provided with a surface 30 against which there seats a securing bolt 31 threaded in a yoke 32, the ends 33 of the yoke engaging 10 suitable eyes 34 carried by the kiln.

When it is desired to remove the tube connection 12 from the kiln, the bolt 31 is unscrewed, the clamps or bolts are removed from the flange 13a, and the yoke 32 is removed. The tube may then be turned and slipped out through the opening in the casting 23. The opening may be closed 15 by means of blocks 36 and 37 of refractory material, having shouldered portions 38 for engaging the flanges 24. The block 36 may be slipped in place first between the projecting wall 20 of the kiln and the supporting shoulder or flange 24, and thereafter the block 37 may be inserted as illustrated. A wall section 39 may then be applied to the construction as shown in Fig. 6, 25 and bolted in place through the yoke and bolt construction described, the bolt 31 bearing upon a strip 40 on the plate 41 which covers the hole in the kiln wall and extends beneath the projection 42 of the lug 27. With this arrangement 30 the connecting section 12 may be removed without removing the tubes 10 from the surface of the kiln. If desired, however, the tubes 10 may be made in sections and may be also removed at the same time.

35 In the manufacture of ordinary Portland cement, it will be understood that the mix may be introduced into the right hand end of the kiln as shown in Fig. 1 (the openings 22 being closed) and fed therethrough at a suitable rate, 40 while a heated gaseous medium is introduced in the other end of the kiln and passed therethrough in countercurrent relation to the passage of the mix to calcine and burn the cement mixture in a manner well known in the production of once burned cement. The once burned 45 Portland cement as it leaves the kiln, may contain excess lime over that which combines with the silica, alumina and ferrite compounds in the first passage through the kiln, or additional lime 50 may be added to it. The mixture is ground and may then be submitted to the second burning, for which operation the same kiln with the tubes 10 in place may be employed.

55 It will be appreciated that one of the advantages of the present invention resides in the fact that kilns which are already in operation for the burning of cement may be employed in the present simple and advantageous manner for carrying out a process involving double burning. In other words, the usual long kiln may be operated by feeding the initial mix adapted to form 60 ordinary Portland cement into the upper end of the kiln and conducting the heating and burning in the usual manner. The product thus obtained may be treated according to the disclosure in the Durbin Patents Nos. 1,700,032 and 1,700,033 and then returned to the same kiln, at the point indicated for the introduction of the mix for the 65 second burning operation, after the material to be initially burned has all passed through.

70 While my apparatus has been described in connection with cement kilns its use is not so

restricted for it may be employed for other purposes.

The terms and expressions which I have employed are used as terms of description and not of limitation and I have no intention, in the use of such terms and expressions, of excluding any equivalents of the features shown and described, or portions thereof, but recognize that various modifications are possible within the scope of the invention claimed.

10 I claim:

1. An apparatus of the type defined, comprising a kiln with a metal shell and a refractory lining, an opening in said shell registering with an overlapping portion of an opening in said refractory lining, a flanged hollow member fixed to the inner surface of said shell and offset from a portion of the opening in the shell, a feed pipe fixed to the outer surface of said shell and a removable connection between one end of said pipe and the kiln, said connection being adapted to pass through the registering portions of said openings, and means for retaining said removable connection upon the shell.

2. In an apparatus of the type described, a kiln having a metal shell with an aperture therein and a refractory lining having an aperture which overlaps the aperture in said shell, an annular member adapted to fit snugly within the aperture in said refractory lining and having a flange adapted to support a removable piece of refractory material, a removable feed pipe connection adapted to extend into the overlapping portions of said apertures, said connection having a flange adapted to contact with the outer portion of the shell around the aperture therein, and means adapted to retain said connection or a closure plate over said shell opening.

3. In an apparatus as defined in claim 2, the means adapted to retain the connection or closure plate comprising a lug adapted to receive a portion of the flange of the connection or a portion of the cover plate and a clamp adapted to bear upon the side of said connection or cover plate opposite said lug.

4. An apparatus of the type described, comprising a kiln having a metal shell and a refractory lining, an opening extending through said shell and lining, a feed pipe fixed to the outer surface of said shell and a removable connection between one end of said pipe and the kiln, said connection being shaped to extend through the openings in said shell and refractory lining and having a flange adapted to bear upon the outer surface of the kiln and to close the opening therein, and clamping means for retaining the said flange against the kiln surface.

5. An apparatus as defined in claim 4, in which the shell of the kiln is provided with a raised flange and the removable connection is provided with a lug adapted to fit thereunder.

6. An apparatus as defined in claim 4, in which the shell of the kiln is provided with a raised flange and the removable connection is provided with a lug adapted to fit thereunder and the clamping means comprises a saddle having its ends positioned in members fixed to the kiln and having a clamping bolt extending through it and bearing upon a portion of the removable connection.

70 THORKILD AVNSOE.
